UNITED STATES PATENT OFFICE.

DAVID F. VAUGHAN, OF RIVERTON, NEW JERSEY.

TAMPING-TOOL.

1,260,603.

Specification of Letters Patent. Patented Mar. 26, 1918.

Application filed July 26, 1917. Serial No. 182,877.

To all whom it may concern:

Be it known that I, DAVID F. VAUGHAN, a citizen of the United States, residing at Riverton, in the county of Burlington and State of New Jersey, have invented certain new and useful Improvements in Tamping-Tools, of which the following is a specification.

My invention relates to improvements in tamping tools for use in tamping railroad ballast and analogous uses.

Tamping tools for this purpose are usually in the form of picks and bars operated by hand or by suitable mechanical devices, the picks and bars having substantially flat, impact, end portions adapted to strike against the material being tamped.

Heretofore tamping tools have been objectionable because, when in use, the impact end portions thereof quickly assume a sharp, rounded or pointed form due to wear occasioned by the friction of the tools against the broken stones, gravel or other material being tamped. This quickly decreases the efficiency of the tools, as the impact end portions thus worn enter between the pieces of ballast material and separate them instead of driving them into the desired position during the tamping operation, and require the impact end portions to be reforged to produce fresh, substantially flat, impact portions thereon. This requirement is not only accompanied by the great objection that the body member of the tool, having the impact end portion, gradually grows shorter under successive reforging operations, but also by the further objection that much time is lost by the tools remaining out of service before, during and after the reforging operations, as it is necessary to send them to suitable shops for this purpose.

The object of my invention is to overcome or greatly lessen the objections above set forth; and I accomplish my object by the provision of a tamping tool of novel, simple and efficient construction: first, having an impact end portion which in service can not be worn into the objectionable sharp, rounded or pointed form; and, second, having the impact end portion thereof formed on an impact member which is removably engaged with the operated body member of the tool and which, when it wears down, may be readily removed from the body member and

substituted by a new one at comparatively little expense.

With this and related objects in view, my invented tool consists of the elements and the combinations of them hereinafter described and claimed.

In the accompanying drawings, illustrating my invention:

Figure 1 is a side view of a tamping tool embodying my invention and showing the body member thereof in the form of a hand bar.

Fig. 2 is a side view of a tamping tool embodying my invention and showing the body member thereof in the form of a pick.

Fig. 3 is a side view of the end portion of the body member of the tool which receives the impact member, having the impact member removed therefrom.

Fig. 4 is a face view of the part shown in Fig. 3.

Fig. 5 is a bottom view of the part shown in Fig. 3.

Fig. 6 is a view similar to Fig. 5, showing the impact member applied to the body member.

Fig. 7 is a perspective view of the impact member removed from the body member.

Fig. 8 is a view similar to Fig. 4, showing the impact member applied to the body member.

Fig. 9 is a view of the parts shown in Fig. 8, showing the impact member in section.

Fig. 10 is a view similar to Fig. 9, showing a modified form of the impact member.

Fig. 11 is a view similar to Fig. 9, showing a modified form of the impact member.

Fig. 12 is a view similar to Fig. 4, showing a modified form of the body member.

Referring to the drawings, 2 designates the body member which may be of any suitable shape and size for its intended purpose to be operated either by hand or by power devices during the tamping operation.

The body member 2 has an end portion 3 which is adapted to be driven down toward the material being tamped; and this end portion 3 is provided with an impact member 4 which is adapted to strike against the said material, during the tamping operation, and which is preferably made separate and detachable from the body member 2, as will be hereinafter explained.

The end portion 3 of the body member 2 is reduced, as illustrated, providing a projecting tongue 5 to receive the impact member 4, and providing shoulders 6 at the base 5 of the tongue 5, and the end portion 3, including its tongue 5, is bifurcated by being split, at 7. In the normal condition of the member 2 the side arms 8 of the bifurcated end portion 3 are shogged or set out of alignment with each other, as clearly shown in Figs. 3 and 5; and the body member 2 is formed of suitable resilient metal adapted when sprung from a normal condition to continue to tend to resume said normal condition, so that when the side arms 8 of the bifurcated end portion 3 are sprung into alignment with each other, as shown in Fig. 6, they will continue to tend to resume their normal or shogged condition, as shown in Fig. 5, for a purpose hereinafter explained. The impact member 4 is preferably made in the form of a band 9 adapted to be driven on to the bifurcated tongue 5, and the member 4 is shaped to fit closely around the sides 25 of the tongue 5 when it is driven on to the same, as illustrated in Figs. 1, 2, 6, 8 and 9, and the member 4 is made of steel or other suitable hard metal adapted to resist wear. When the impact member 4 is driven on to 30 the tongue 5, the sides of the bifurcated end portion 3 of the body member 2 will be sprung from the position shown in Fig. 5 and into alignment with each other, as shown in Fig. 6, so that, after the member 4 has 35 been driven on to the tongue 5, as shown in Figs. 1, 2, 6, 8 and 9, the side arms of the bifurcated end portion 3, in tending to resume their said normal or shogged condition, will act against the impact member 4 surrounding them in a manner to firmly hold the member 4 in place upon the body member 2 and prevent its accidental removal or displacement therefrom.

The sides of the free end of the tongue 5 are beveled at 10, to permit the impact member 4 to be driven on to the same, as will be readily understood; and, the member 4, when it is applied to the body member 2, is driven on to the tongue 5 until the inner or basal 50 end of the member 4 comes into engagement with the shoulders 6 which prevent further inward movement of the member 5 both while being applied to the body member 2 and afterward when the tool is in service. 55 The size of the impact member 4 is such that, after it has been driven on to the body member 2 and into engagement with the shoulders 6 thereof, the outer or impact end portion 11 of the member 4 will project beyond the outer end of the tongue 5. This impact end portion 11 of the member 4 is filled with a metal or other suitable material 12 which is softer and which will wear down much quicker than the surrounding 60 metal forming the band 9; and the material 65

12 is held in place within the band 9 by frictional engagement therewith, the material 12 being forced into or otherwise suitably applied to the band 9 before the impact member 4 is applied to the body member 2. 70

After the impact member 4 has been driven on to the body member 2, the ends of the inner or basal end of the member 4 project beyond the outer face of the body member 2 to be engaged by a hammer or other suitable instrument and thereby permit the member 4 to be readily driven off from the tongue 5, when it is desired to remove the impact member from the body member. 75

When the impact member 4 is in place 80 upon the body member 2, the face of the free outer end or bottom of the impact end portion of the member 4 formed by the band 9 and material 12 forms the impact face which strikes against the material being 85 tamped, and, as this face of the hard band portion 9 of the member 4 always surrounds the softer material 12 within the same, until the outer or impact end of the member 4 is worn down to the outer end of the tongue 5, 90 it will be impossible for the impact end of the member 4, as a whole, to be worn into a sharp, rounded or pointed form, and its character will always be such as to provide a broad and efficient impact surface which 95 will engage the pieces of broken stones, gravel or other material being tamped and drive them into the desired tamped position.

After the outer end portion of the impact member 4 has been worn down to or near the outer end of the tongue 5 of the body portion 2, the worn impact member 4 is removed from the body member 2 and a new impact member from a lot kept on hand 100 for the purpose is driven on to the tongue 5 in substitution for the worn member, as previously explained, and the tamping tool is again ready for service, and little time is lost in changing the impact members. 110

As the impact members 4, made in accordance with my invention, may be manufactured at little cost, the cost of maintaining the tamping tool in an efficient condition will be slight, and the length of the body 115 member 2 carrying the impact member 4 will remain unimpaired.

In the modification illustrated in Fig. 10, I have omitted the filling 12, shown in Fig. 9, from the band portion 9 of the impact 120 member 4; in the modification illustrated in Fig. 11, I have shown an impact member having a band portion 13 which surrounds the tongue 5 of the body member 2 and which has a closed outer end portion 14 125 forming the impact end of the member 4 and being formed integral with the band portion 13; and in Fig. 12, I have shown the side arms 8 of the bifurcated end portion 3 of the body member 2 separated laterally 130

but in alinement with each other, in the normal condition thereof, as shown by full lines, and being adapted to be sprung toward each other to the condition shown by dotted lines, when the impact member is driven on to the same, the arms 8 being beveled, at 15, to permit the impact member to be driven on to them.

I claim:

10 1. A tamping tool comprising a body member, and a removable impact member mounted on the body member, said body member having a resilient part sprung from a normal condition and holding said members in engagement with each other in tending to resume its normal condition.

20 2. A tamping tool comprising a body member having a bifurcated portion the sides of which are sprung from a normal condition, and a removable impact member mounted on the body member and held in place thereon by said sides tending to resume said normal condition.

25 3. A tamping tool comprising a body member having a bifurcated portion the sides of which are sprung from a normal condition, and a removable impact member in the form of a band surrounding said bifurcated portion and held in place thereon by said sides tending to resume said normal condition.

35 4. A tamping tool comprising a body member having a reduced end portion providing a shoulder at the base thereof, said end portion being bifurcated and the sides being sprung from a normal condition, and a removable impact member embracing said reduced end portion and being adapted to engage said shoulder and being held in place on said end portion by said sides tending to resume said normal condition.

40 5. A tamping tool comprising a body member, and a removable impact member mounted on the body member, said impact member comprising a band surrounding a portion of the body member and having a closed impact end portion.

6. A tamping tool comprising a body

member, and a removable impact member mounted on the body member, said impact member comprising a band surrounding a portion of the body member and having an impact portion projecting beyond the same and having its impact portion closed by a filling of material softer than the material forming the band.

7. A tamping tool comprising a body member, and a removable impact member mounted on the body member, said impact member comprising a band surrounding a portion of the body member and having a closed impact end portion, one of said members having a resilient part sprung from a normal condition and engaging a part of the other member, and said members being held in engagement with each other by the action of said part in tending to resume its normal condition.

8. A tamping tool comprising a body member, and a removable impact member mounted on the body member, said impact member comprising a band surrounding a portion of the body member and having a closed impact end portion, said body member having a resilient part sprung from a normal condition and holding said members in engagement with each other in tending to resume its normal condition.

9. A tamping tool comprising a body member having a bifurcated portion the sides of which are sprung from a normal condition, and a removable impact member mounted on the body member and held in place thereon by said sides tending to resume said normal condition, said impact member comprising a band surrounding said bifurcated portion and having a closed impact end portion.

10. A tamping tool having an impact member comprising an inner portion and an outer portion embracing the inner portion, said inner portion being formed of softer material than the outer portion.

In testimony whereof I affix my signature hereto.

DAVID F. VAUGHAN.
